SAFETY DEVICE

George C. Matson, Brookfield, Ill., assignor to
Western Electric Company, Incorporated, New
York, N. Y., a corporation of New York

Application February 6, 1943, Serial No. 475,033

9 Claims. (Cl. 74—608)

This invention relates to safety devices and more particularly to machine guarding devices.

In many machine operations it may be desirable that guards be provided which will protect the machine operator from the exposed moving parts of the machine. In some cases, the guards are attached directly to the die assemblies, for example, in punch presses, it is sometimes the practice to provide each of the individual tool assemblies with a guard. While this practice is satisfactory from the point of view of safety, it may require a special design of guard for each assembly and, thus, increase the cost of the apparatus considerably.

An object of the present invention is to provide an efficient and effective universal machine guarding device.

In accordance with one embodiment of this invention, a machine guard may be provided comprising a three-sided enclosure of telescoping rods and tubes adapted to be attached to a machine and adjustable to screen die assemblies of varying dimensions.

Other objects and advantages of the present invention will be apparent from the following detailed description taken in conjunction with the following drawings, wherein

Fig. 1 is a fragmentary front elevation of a punch press having a guard constructed in accordance with the present invention attached thereto;

Fig. 2 is a side view of the same;

Fig. 3 is an enlarged horizontal section along the line 3—3 of Fig. 1, and

Fig. 4 is an enlarged, fragmentary, vertical section along the line 4—4 of Fig. 2.

Referring now to the drawings, and particularly to Fig. 1, a part of a punch press is illustrated comprising a ram 10 vertically mounted and slideable between upright frame members 11 and 12; a punch 13 is attached to the lower end of the ram 10 and cooperates with a fixed die 14 which is, in turn, mounted on a fixed bed 15 integrally formed with the frame members 11 and 12. As may be seen in Fig. 2, the upright members 11 and 12 are recessed at 16 to facilitate insertion of the stock and operation of the press. This press design is sometimes referred to as the "C" type.

While this invention will be described in connection with providing a guard for a press of this design, it will be understood that this is merely illustrative of one form of guard embodying the present invention.

In order to provide an adjustable mounting for the guard, a pair of L-shaped brackets having vertical arms 20 and horizontal arms 21 fixed per-

pendicularly to the lower ends of the vertical arms is attached to the front of the frame members 11 and 12 by bolts 19, the bolts extending through a slot 22 formed through each of the arms 20. These brackets are substantially square in cross section and heavy enough to support the weight of the guard without yielding.

A pair of horizontally positioned supporting members 23 are slidably mounted on the horizontal arms 21 of these brackets, and extend rearwardly perpendicularly to these arms 21. A pair of wing nuts 24 are threaded into the ends of the supporting members, which are enlarged and provided with squared apertures to receive the square

cross-section arms 21 of the brackets. These nuts, when tightened, lock the members 23 to the arms 21. A pair of downwardly extending bars 25 are attached perpendicularly to the rearwardly extending ends of the supporting members 23 and are mounted in a vertical plane, as shown in Fig. 2, to serve as a support for a plurality of horizontally positioned tubes or rods 28, which are fixed perpendicularly to the bars 25, as shown. A corresponding number of tubes or sleeves 29 are mounted on supporting bars 30 which are parallel to the bars 25. These sleeves 29 extend perpendicularly to the bars 30 to receive the rods or tubes 28 which are sufficiently smaller in diameter than the interior diameter of tubes or sleeves 29 to provide a sliding fit.

It will be apparent from the foregoing description that the areas adjacent the sides of the punch and die assembly are thus screened by the cooperating rods 28 and sleeves 29, and that the rods and sleeves are laterally adjustable with respect to each other to adapted the screen to punch and die assemblies of greater or less width. A pair of clamps 31 and associated wing nuts 32 are fixed to one of the tubes 29 on each side of the screen and engage the rod within the tube to lock the rods to the tubes when the desired width of the side screen has been obtained by adjusting the rods and tubes together or apart, as may be required.

The front area of the press is guarded by a second set of cooperating horizontal rods and sleeves 35 and 36, respectively. The rods 35 may be fixed perpendicularly, as shown in Figs. 1 and 3, to one of the supporting bars 30 while the other bar 30 supports the sleeves 36. Lateral adjustment of the side screens with respect to each other will correspondingly alter the width of the front screen formed by the cooperating rods and sleeves 35 and 36, which are slidably one within the other. Tightening the two wing nuts 24 on the horizontal bracket arms 21 will lock the side

screens in lateral position and accordingly maintain the front screen and side screens in their adjusted positions.

A horizontal bar 40 is mounted perpendicularly to each bar 30 at a point near its lower end and a plurality of horizontal rods 41 extend perpendicularly to the bar 40 through suitably formed apertures in each bar 40. The inner ends of the rods 41 are, in turn, attached to a horizontally positioned bar 42, which is mounted substantially parallel to the bar 40. A wing nut 43 and associated clamp 44, fixed to each of the apertured supporting bars 40, are provided to lock the tubes or rods 41 in position with respect to the supporting bar 40. Thus the rods 41 are adjustable as a unit and form a horizontal screen on either side of the machine.

In order to permit the operator to observe the operation of the punch press and at the same time to protect him from possible injury, a window 45 mounted on vertically positioned arms 46 is provided. These arms 46 are attached to the front ends of the horizontal bars 42 and extend downwardly a sufficient distance to provide a support for a window of the desired size. This window comprises, as shown in Fig. 3, a single sheet of transparent, fracture resistant material, fixed to one of the vertical arms 46, and slideable in channeled members 47, fixed to the other of the arms 46.

In order to screen the lower portion of the punch and die assembly, a number of sleeves or tubes 50 are perpendicularly mounted on the vertical arms 46 and extend rearwardly therefrom to receive cooperating rods or tubes 51, slideable therein. These rods 51 are in turn mounted on vertical downwardly extending bars 52, which are fixed to the rear ends of the bars 42. The rods 51 extend in a plane substantially parallel to the arms 46.

In the operation of this apparatus, after the required adjustments have been made to screen the tools from an operator, a strip 55 of stock material may be fed to the punch and die assembly through one of the apertures in the small lower screens comprising the cooperating sleeves and rods 50 and 51.

It will be apparent from the foregoing description that this guard is adaptable to die assemblies of varying height by loosening the bolts 19, and moving the entire guard up or down as may be required, that it is adaptable to die assemblies of varying width by loosening the wing nuts 24 and wing nuts 43 and moving the side screens together or apart, the front screen and window adjusting itself accordingly, and that it is adaptable to die assemblies of varying breadth by loosening the wing nuts 32 and moving the front screen and window toward or away from the die assembly as necessary. Thus, instead of requiring differently designed and shaped guards for each type of machine and for each die assembly, a single standard guard design constructed as described herein may be employed.

In addition, because of the particular design of this guard and because of its easy adjustability, the screens may be positioned very close to the particular die assembly being used with a machine. This feature is of particular importance where a thin strip of stock is used because, after the punching operation, the strip has little strength and if the strip is required to bridge a relatively long distance from one side of the guard to the other, it is very likely to break. In the present apparatus, because the screens may

be positioned immediately adjacent the die assembly, in most cases this difficulty is largely obviated.

What is claimed is:

- 5 1. A safety guard for a machine comprising a plurality of screens, one pair of screens being mounted and spaced in substantially parallel relationship, a third screen mounted on and between said pair of screens and attached to one end of each of said pair of screens, said screens cooperating to form a multi-sided enclosure, a plurality of substantially parallel cooperating sleeves and rods forming said screens, said sleeves receiving said rods, the space between said pair of screens being adjustable, said third screen being extensible and contractible as the spacing between said pair of screens is altered, said pair of screens also being extensible and contractible to adapt them to machines of varying dimensions, and means for mounting said screens on a machine.
- 10 2. A guard for a machine comprising a front screen, a plurality of relatively adjustable elongated members forming said screen, the width of said screen being adjustable to the width of said machine, a pair of side screens of similar construction associated with said screen and mounted substantially at right angles to the ends thereof, said side screens cooperating with said front
- 15 30 screen to form a multi-sided enclosure about a portion of said machine, a pair of screens mounted at substantially right angles to said aforementioned side screens at the lower ends thereof, a third pair of spaced screens associated with said second pair, said third pair of screens extending in a plane substantially parallel to the plane of said side screens and at substantially right angles to the plane of the second pair of screens, a window enclosing the front area between said third pair of screens, and means for attaching said guard to a machine.
- 25 3. A machine guard comprising a plurality of relatively adjustable elongated members, said members cooperating to form a pair of spaced side screens, means for mounting said side screens on a machine, a third screen formed from similar elongated members and mounted at right angles to said first pair of screens to form a three-sided enclosure, a plurality of elongated members fixed to said side screens and extending perpendicularly thereto, a second pair of screens attached at right angles to the side screens, and a window mounted between said second pair of screens, the width of said window being adjustable as the spacing between said pair of side screens is altered.
- 35 4. A machine guard comprising a pair of spaced, substantially parallel screens, the width of said screens being adjustable, and a third screen at right angles to said screens and supported thereby, the width of said third screen being adjusted as the spacing between said pair of screens is altered.
- 40 5. A machine guard comprising a pair of spaced substantially parallel screens, the width of said screens being adjustable, a second pair of screens mounted at substantially right angles to the base of the first pair of screens, and a third pair of screens mounted at substantially right angles to said second pair of screens and extending in a plane substantially parallel to said first pair.
- 45 6. A guard for a machine comprising a pair of spaced screens, means for supporting said screens on a machine in substantially parallel

planes, and an adjustable third screen positioned between said screens and supported thereby, the width of said third screen being adjusted by moving said supporting screens.

7. A machine guard comprising a pair of spaced substantially parallel screens, the width of said screens being adjustable, a second pair of screens mounted at substantially right angles to the base of the first pair of screens, a third pair of screens mounted at substantially right angles to said second pair of screens and extending in a plane substantially parallel to said first pair, and a window supported by said third pair of screens, the width of said window being adjusted as the spacing between said first pair of screens is altered.

8. A machine guard including a screen, the width of said screen being adjustable, a second screen mounted at one end of said first screen and extending in a plane substantially perpendicular to said first screen, said screen being adjustable in size in its plane with respect to the supporting screen, and a third screen mounted at substantially right angles to one end of said

second screen and extending in a plane substantially parallel to the plane of said first screen, the spacing between the first and third screens being adjusted by adjusting the effective width of said second screen.

9. A machine guard comprising a pair of spaced, substantially parallel screens, the width of said screens being adjustable, a second pair of screens mounted at substantially right angles to the base of said first pair of screens, a third pair of screens mounted at substantially right angles to said second pair of screens and extending in a plane substantially parallel to said first pair, an adjustable screen mounted between said first pair of screens, the width of said screen being adjustable as the spacing between said first pair of screens is adjusted, and a window, the width of which is adjustable, mounted between said third pair of screens and substantially parallel to the screen mounted between said first pair of screens, the width of said window being adjustable as the spacing between said third pair of screens is adjusted.
